(57) CLAIM

The ornamental design for a picture support, as shown and described.

DESCRIPTION

The present invention is directed to an article for supporting pictures and wall hangings.

FIG. 1 is a front cross-sectional view of the picture support showing my new design;

FIG. 2 is a front elevation view thereof; and,

FIG. 3 is a top view thereof.

1 Claim, 1 Drawing Sheet

FIG. 1

FIG. 3
